HEAT-TRANSFER SYSTEM FOR ELECTRIC TRANSFORMERS OR OTHER DEVICES.

Application filed June 18, 1926. Serial No. 116,769.

This invention relates generally to improvements in heat transferring systems for cooling oil filled electric transformers or for other heat extraction operations.

5 The invention has for its principal object to provide a novel construction and arrangement of heat transferring or cooling apparatus, which, although adapted for service in connection with other forms and types of 10 mechanical and electrical apparatus, is especially adapted to the cooling of oil filled electric transformers serving power and lighting circuits.

In the past, such oil filled transformers 15 have generally been cooled either by passing cold water through coils in the upper part of the oil jackets or tanks or by radiators located around the sides of the oil jackets or tanks and connected to the top and bottom 20 of the tank by pipes to promote proper circulation. The first method of cooling has not been found satisfactory because of the quantity of water required to cool large sizes 25 of transformers as well as by reason of the care necessary to be exercised in order to prevent freezing. The second method of "self cooling" large transformers involves the use of a multiplicity of radiators surrounding the 30 transformers, all of which are connected top and bottom therewith. Such construction requires a large ground space, while at the 35 same time, especially in connection with large size transformers, produces a very unwieldy construction making it necessary to remove or dismantle the radiator elements when shipping the transformers. Due to the restricted 40 ground space generally available for power line transformers which must be located at load centers, the radiators are constructed 45 and arranged vertically, and consequently the upper parts of the same are not efficient in cooling function by reason of the fact that the same are bathed in the hot air rising from the lower parts thereof; furthermore, owing 50 to the usually restricted ground space available, it is not possible to provide sufficient radiator capacity so that cold oil leaving the bottom of the radiator is approximately at the desired ambient temperature when the 55 transformer is continuously loaded one hundred per cent. To obtain great radiator capacity, additional radiators have been placed above the transformer, but this location has been found undesirable by reason of the in-

creased likelihood of oil leakage caused by the 55 increased head of oil.

By the present invention I have sought to provide a cooling or heat transfer system of such novel construction, arrangement, and mode of operation as is adapted to overcome 60 the objections above mentioned, while at the same time providing a construction permitting a considerable reduction in the volume of oil required for the transformer while nevertheless permitting greater loads to be 65 carried by the transformer without overheating. To this end my invention broadly comprises means to apply a refrigerating medium in such manner as to rapidly transfer the heat from the transformer oil bath, in combination 70 with relatively remote radiator means for relieving the refrigerant of absorbed heat and circulating the same in the performance of its cooling function. My invention also includes auxiliary cooling means cooperating 75 with the bottom or lower end of the transformer oil bath, and operating to assist the desired cooling effects, especially when the transformer is subjected to heavy overload.

Other objects of this invention, not at this 80 time more particularly enumerated, will be clearly understood from the following detailed description of the same.

The invention is clearly illustrated in the accompanying drawings, in which:—

Figure 1 is in part a front elevation and in part a sectional view of my novel heat transfer or cooling apparatus as applied to an electric transformer; Figure 2 is in part a side elevation and in part a sectional view of 90 the same; Figure 3 is an enlarged fragmentary sectional view of the water jacket element of the auxiliary cooling means for the oil jacket or tank.

Figure 4 is a sectional view of a modified 95 means for supplying water to the water jacket element of the auxiliary cooling means for the oil jacket or tank.

Similar characters of reference are employed in all of the herein described views, 100 to indicate corresponding parts.

Referring now to said drawings, the reference character 10 indicates any suitable type of electric power transformer which is enclosed in the usual oil jacket or tank 11. 105 Spaced between the transformer 10 and the wall of the oil jacket or tank 11 is a baffle member 12, the upper end of which termi-

nates short of the closed top end of said tank, while the lower end terminates short of the tank bottom, thus providing an inner or ascending circulation path 13 and an outer or descending circulation path 14 for the oil in which the transformer is submerged. Said circulation paths 13 and 14 thus communicating one with the other at their upper and lower ends.

10 Said transformer 10 and the enclosing oil jacket or tank 11 are supported upon a suitable base 15, usually made of concrete.

Connected with said oil jacket or tank 11, so as to extend around the exterior thereof adjacent to its lower end, is an annular closed receptacle 16, the inner wall of which is preferably provided by the wall of said oil jacket or tank 11.

Mounted on the roof of the structure in 20 which the transformer is housed, or in any other convenient location, which, if desired, may be more or less remote from the transformer itself, is a radiator member. This radiator member may comprise suitably disposed headers 17 connected in intercommunicating relation by lateral connecting pipes or ducts 18, and a collector member or pipe 19 which is in a plane beneath said headers 17, and which is in communication therewith 30 through a plurality of transversely disposed radiator pipes 20. Connected between the upper end of said receptacle 16 and the radiator headers 17 is a vapor delivery pipe 21. Connected between one end of said collector 35 member or pipe 19 and the lower end of said receptacle 16 is a return pipe 22. Suitably disposed beneath the above described radiator member is a water catch basin and reservoir 23 which is connected by a pipe-line 24 through a suitable force pump 24' with a 40 sprinkler head 25 arranged above and adapted to shower the radiator with water when desired, for example, on very hot days, thus increasing the cooling efficiency of the radiator by the evaporation of the water on the 45 surfaces of the radiator pipes 20.

Also connected with said oil jacket or tank 11, so as to extend around the exterior thereof adjacent to its upper end, is a second annular closed receptacle 26, the inner wall of which is preferably provided by the wall of said oil jacket or tank 11. Also mounted on the roof structure in which the transformer is housed, or in any other convenient location, which, if desired, may be more or less remote from the transformer itself, is another radiator member. This radiator member may also comprise suitably disposed headers 27 connected in intercommunicating relation by lateral 55 connecting pipes or ducts 28, and a collector member or pipe 29 which is in a plane beneath said headers 27, and which is in communication therewith through a plurality of transverse radiator pipes 30. Connected between the upper end of said receptacle 26 and

the radiator headers 27 is a vapor delivery pipe 31. Connected between one end of said collector member or pipe 29 and the lower end of said receptacle 26 is a return pipe 32.

Connected with the lower end portion of 70 said oil jacket or tank 11, so as to surround the same, is a water jacket member 33 open at its upper end and provided with a marginal lip-portion 34 at its upper periphery. Arranged in the bottom of said water jacket member 33 is a water supply pipe 35 having outlet orifices 36; said water supply pipe 35 being connected with a feed-pipe 37 leading from a suitable source of water supply, such, for example, as a city main. Formed in said 75 base 15, or otherwise provided, beneath the lip-portion 34 of said water jacket member 33 is a catch-trough 38 from which leads a suitable drain pipe 39 for leading away the water caught thereby. In rural districts or 80 other locations lacking a water supply system, a modified means for storing and feeding cool water to the water jacket member 33 may be provided. One form of water supply means suitable to such conditions is shown in 85 Figure 6 of the drawings, the same comprising a storage cistern 40, leading into the upper end of which is a water supply pipe 41 to deliver water from a suitable source, such as a stream, well or the like. Said supply 90 pipe 41 is preferably provided with a float controlled shut-off valve 42. Extending upwardly from the bottom of said cistern 40 is a cooler pipe 43 which is open at its upper end, said upper end being located below the 95 normal water level of said cistern, so that the warmer water at the said upper level may flow into said upper end of the cooler pipe 43. The lower end of said cooler pipe 43 is provided with an outlet port 44 adjacent to the bottom of said cistern. Located within the upper end of said cooler pipe 43 is a refrigerating element 45, which may be in the form of a tank or receptacle, which contains a suitable refrigerating medium, such, for 100 example, as ether. Connected in communication with said ether tank or receptacle 45 is a condenser 46 which is exposed to atmosphere above the cistern, said condenser 46 having an intake conduit 47 and a return conduit 48 suitably connected in communication 105 with said ether tank 45. The cistern is filled with water, the warmer portion of which, at the upper level of the cistern, will flow into the upper end of the cooler pipe 43 and in contact with the ether tank 45, to which the heat of the water is transferred, thus causing the ether within the tank 45 to boil. The ether vapors pass upwardly through the intake conduit 47 into and through the condenser 46, being thereupon condensed and returned through the return conduit 48 back to the ether tank 45. The warm water thus 110 entering the upper end of the cooler pipe 43, and becoming chilled by the refrigerating 115

120 element 45, is led through the water jacket member 33 to the upper end of the water jacket 125 member 33, where it is distributed through the vapor delivery pipe 31 to the radiator headers 27. The warm water leaving the radiator headers 27 is led through the return pipe 32 to the lower end of the water jacket member 33, where it is distributed through the water supply pipe 35 to the 130 storage cistern 40. The water jacket member 33 is provided with a suitable drain pipe 39 for leading away the water caught thereby.

element 45 descends the cooler pipe 43 to pass into the bottom of the cistern through the outlet port 44, displacing warmer water, which rises to the upper level of the cistern 5 for circulation through the cooler pipe 43. In this manner the stored water in the cistern is cooled to approximately the lowest ambient temperature occurring during the day, so as to be in most efficient condition for use 10 when needed, as will be hereafter more fully described. Connected with the bottom of said cistern 40 is the water feed pipe 37 leading to the water jacket member 33, and if gravity flow is not possible a pump 49 may be 15 provided in the line thereof to compel proper delivery of the water to said water jacket member 33. If desired, the drain pipe 39 leading from the catch-trough 38 associated with the water jacket member 33, may be led 20 back to the cistern 40, as indicated in said Figure 6.

For additional cooling effect upon the transformer, when the same is subjected to extra heavy overload, I may also provide a 25 cooling coil 50 arranged in the bottom of the oil jacket or tank 11 for direct contact with the oil content of the latter. Suitable means is provided for circulating through said cooling coil a refrigerating medium.

30 The operation of the novel heat transfer system in connection with its application to electric power line transformers is as follows. It is understood that by reason of the fluctuating load to which such transformers are 35 subjected, that the generation of heat desired to be dissipated is greatest at those periods in which the transformer is subjected to peak loads and overloads. Power transformers are generally subject to comparatively light 40 loads from about 10 p. m. in the summer until approximately 7 a. m. From 7 a. m. until 5 p. m. they are generally operating under approximately full load with a tendency to a slight decrease until dark, but from the fall 45 of darkness until about 10 p. m. the same are running under peak load conditions, and they may during this period be subjected to a very heavy overload for a duration of approximately two hours. Under these conditions 50 the transformer is usually in a comparatively cool condition when thrown on load early in the morning.

Under conditions rising from light loads to approximately full loads, the transformer 55 coils will generate more or less heat, which is absorbed by the oil bath in which the same are submerged, the oil being caused to circulate within the oil jacket or tank 11 around the baffle member 12, as the hot oil rises 60 around the inner or transformer side of the latter and the cooler descends down the outer side of the same. The receptacle 16 which encircles the oil jacket or tank 11 is supplied 65 with a fluid medium adapted to readily take up heat; for example, ether may be employed 70 as such medium. As the oil heats up, the hotter portions thereof rise to overflow down the outer side of the baffle member 12, and are thus caused to contact with that portion of the oil jacket or tank wall to which the 75 surrounding receptacle 16 applies the ether. The heat of the oil is thereupon transferred through said wall portion to the ether, thereby cooling the oil, and the cool oil descends to pass around the lower end of the baffle- 80 member 12 to again surround the transformer coils to receive the heat generated by and transferred therefrom. In this manner the circulation of oil is accelerated, while at the same time the heat transferred thereto, is in 85 turn transferred to the cooling medium provided by the ether, all of which assures a flow of oil around the transformer coils which is cooled to a temperature adapted to dissipate the heat of the transformer at temperature 90 rises not exceeding 20 degrees C. above ambient temperature. The heat transferred to the ether in the receptacle 16, causes the same to boil, whereupon the vapor produced ascends through the delivery pipe 21 to the 95 headers 17 of the connected radiator member, such vapors in passing through the radiator pipes 20 being relieved of their heat by radiation to the atmosphere, and thereby being condensed for collection by the collector member 19 for return through the return pipe 22 to the receptacle 16 for repetition 100 of the cooling process involved. By the above described operations, the oil bath around the transformers may be relieved of the heat 105 transferred thereto and kept in practically operative cooling condition so long as the temperature of the hot oil at the top of the jacket or tank 11 remains under 50 degrees C., and consequently the transformer is relieved of heat under fluctuating load conditions from light to approximately full loads, and under moderate atmospheric temperature. If, by reason of excess generation of 110 heat in the transformer, or by reason of appreciable rises of atmospheric temperature, the temperature of the hot oil of the jacket or tank 11 rises above 50 degrees C., additional cooling or heat transferring means is automatically brought into action. This additional means comprises the receptacle 26 which surrounds the upper part of the oil jacket or tank 11, and in which is introduced a fluid medium operative at higher temperatures to take up heat; such a fluid medium as 115 alcohol may be employed in this connection. When the temperature of the oil at the top of the jacket or tank 11 rises to 50 degrees C. or more up to approximately 85 degrees C., the contact of the hot oil with that portion 120 of the jacket or tank wall coincident to the receptacle 26 will permit the transfer of heat from the oil through the wall to the alcohol in said receptacle 26, whereby the temperature of the oil is reduced, while being subject 125 130

to further reduction when passing the zone of the ether receptacle 16, so that by the time it returns to the bottom of the jacket or tank for up-flow around the transformer coils it 5 has been cooled down to approximately 45 degrees C. when ambient temperature is about 40 degrees C. The transfer of heat to the alcohol in the receptacle 26 causes the same to boil, whereupon the vapors produced 10 will ascend the delivery pipe 31 to the headers 27 of the connected radiator member, to flow through the radiator pipe 30 through which the heat thereof is dissipated by radiation thus condensing the alcohol for collection 15 in the collector member 29, to be thence returned through the return pipe 32 to the receptacle 26 for repetition of the cooling processes involved. If the temperature of the hot oil approximates 80 degrees C., it is 20 advisable to start the pump 24' supplying the water spray over the radiator member elements 17, 18, 19, 20, whereby the efficiency thereof is greatly increased, and the cooling effect of the ether medium in the receptacle 25 16 is maintained efficiently operative.

From the above description it will be apparent that my novel system of heat transfer or cooling devices will automatically operate to dissipate the undesired heat generated by 30 electric power transformers under varying conditions and under loads varying from light loads to full loads, and even under overloads of comparatively short duration.

Under conditions of heavy overloads, especially when the same are of appreciable duration, I have found it desirable to provide additional auxiliary cooling means already above described, which may be brought into operation at will according to need, and 35 which function as follows. By this auxiliary cooling means water is circulated through the water jacket member 33 from a suitable source of supply as already above set forth. Cool water is delivered to the water supply 40 pipe 35 in the bottom of said jacket member 33, and is discharged into the interior of the latter through the orifices 36 in said supply pipe. The water fills the jacket member 33 so as to surround the lower portion of the oil 45 jacket or tank 11, whereby additional heat may be absorbed from the cooled oil descending the outer side of the baffle member 12 for up-flow around the hot transformer coils. The additional heat thus transferred to the 50 water is carried off thereby, as the water overflows the lip-portion 34 of the water-jacket 33, and the warm water is replaced by the incoming cool water. This additional cooling effect enables the transformer to carry a heavy 55 overload, and yet, owing to cooling of the oil by the main cooling elements, attains the desired additional cooling effect with a comparatively small lift in temperature thus 60 making for economy.

Still further cooling effects under high

overload conditions in the transformer may be attained by the use of the cooler coil 50 in the bottom of the oil jacket or tank 11, to which a cooling medium is served in the manner already above set forth. Inasmuch as this 70 cooler coil 50 will be used when it is desired to transfer excess heat arising under extra heavy overload conditions of the transformer, time is permitted during relatively normal load conditions or off peak hours to reduce 75 the cooling medium, which may be water or brine, to approximately freezing temperature, and thus to store its capacity for absorbing heat ready for application during peak hours. 80

It will be understood that in the accompanying drawings and the above specification, the invention has been shown and described merely in preferred form and by way of example and as applied more especially to 85 electric power transformers, but obviously many alterations and variations may be made therein and in its mode of application which will still be comprised within its spirit. For instance I may wish to employ a refrigerant 90 having a low boiling point in all of the aforesaid cooling means, thus keeping the temperature of the transformer relatively close to the temperature of the ambient air during off peak hours; or I may employ a refrigerant 95 in all the cooling means having a relatively high boiling point, e. g. approximately 10 degrees C., so that at very low ambient temperatures, e. g. minus 30 degrees C. or less, the cooling means will not circulate, but will actually act as a heat insulator to maintain a 100 relatively high transformer temperature during off peak loads, and thereby prevent extreme temperature changes in the transformer with consequent tendency to mechanical 105 shrinkage and expansion strains. Generally speaking, therefore, it is to be understood that this invention is not limited to any specific form or adaptation except in so far as such limitations may be specified in the 110 claims. 115

I wish to here emphasize the following advantages which I attribute to my present invention.

First. The radiators may be located more or less remotely from the apparatus to be cooled, and in the most efficient and economical situation, thus permitting the transformer to be installed in a pit or basement if desired.

Second. By the use of two or more separate annular cooling zones or receptacles in association with the apparatus to be cooled, each provided with a corresponding radiator, and the same being respectively provided with suitable refrigerants, I am able to effect two or more temperatures of radiation, the higher temperature refrigerant being adapted to dissipate most of the heat in a cheap and economical manner, while the lower temperature refrigerant is effective not so much 125 130

to extract large quantities of heat as to pull down the temperature of the bottom oil.

Third. By my system I provide means for storing up the coolest available ambient temperature which will generally occur at off peak load periods when it is not needed, so that the same is available for use during a peak ambient temperature or during a peak load period or both; and, furthermore, I provide means for using this stored cold medium to obtain the last few degrees of bottom oil cooling, returning the cold medium to its place of storage with only a relatively small lift in temperature, whereby the coolest ambient temperature which occurs at off peak conditions will be required to extract only a few degrees of heat.

Fourth. By using my novel low temperature brine tank I may greatly increase the overload capacity of a transformer by supplying to the transformer coils oil of very low temperature.

Fifth. By a choice of suitable refrigerant or refrigerants I may cause such refrigerant to serve as a heat insulator at low temperatures while at the same time becoming a very effective cooling agent at high temperatures.

Having thus described my invention, I claim:

1. In combination with an apparatus having a circulating fluid to be cooled, independent means for applying refrigerants in separate volumes respectively in contact with different portions of said apparatus to which heat from said circulating fluid may be transferred at different temperatures, one said means being located adjacent the zone of maximum heat to serve as a means to step down maximum temperature of said circulating fluid, the other said means being located at a position according to the direction of circulation of the fluid to be cooled adapted to further reduce the temperature of the fluid adjacent the low temperature point of its circulation, a radiator means for each volume of refrigerant, means for conducting the vapor of each volume of refrigerant to the radiator corresponding thereto, and means to return each condensed refrigerant respectively in contact with the respective portions of said apparatus served thereby as aforesaid.

2. In combination with an electric transformer, an enveloping tank containing oil, means for applying a volatile refrigerant in juxtaposition with said oil to extract heat therefrom by vaporization of the refrigerant, a radiator means located remotely from and above said volatile refrigerant applying means, means to permit the vapor of the refrigerant to expand into said radiator to be relieved of its heat and condensed, and means to return by gravity the condensed refrigerant to said applying means.

3. In combination with an electric trans-

former, an enveloping tank containing oil, means for applying a refrigerant in juxtaposition with said oil to which heat from said oil may be transferred, a radiator means, and means for conducting the vapor of the refrigerant to said radiator to be relieved of its heat and condensed, means to return the condensed refrigerant to said means in juxtaposition with said oil, and means cooperative with said radiator to shower the same with water to obtain additional cooling effects of evaporation.

4. In combination with an electric transformer having an enveloping oil jacket the oil content of which is subject to circulation, means for partially cooling said oil, means for applying a refrigerant in juxtaposition with said partially cooled oil to which heat from said partially cooled oil may be transferred, a radiator means, means for conducting the vapor of the refrigerant to said radiator means to be relieved of its heat and condensed, and means to return the condensed refrigerant to said means in juxtaposition with said partially cooled oil.

5. In combination with an electric transformer having an enveloping oil jacket the oil content of which is subject to circulation, means for partially extracting the heat from said oil, means for storing an additional reserve cooling medium so that it may yield its heat to the ambient air when the latter is at a minimum temperature, means to retain said reserve cooling medium at a minimum temperature under rising ambient air temperature, and means for applying the heat absorbing capacity of said reserve cooling medium more or less rapidly to reduce the temperature of said oil during relatively short peak overload conditions of said transformer.

6. In combination with an electric power transformer, an enveloping tank containing oil subject to convective circulation, an exterior receptacle around said tank arranged to hold a refrigerant in contact with the tank wall to thereby extract heat from said oil, a radiator means, means for conducting the vapor of the refrigerant to said radiator to be relieved of its heat and condensed, and means to return the condensed refrigerant to said receptacle.

7. In combination with an electric power transformer, an enveloping tank containing oil subject to convective circulation, a plurality of independent annular receptacles vertically spaced around said tank and respectively adapted to hold refrigerants effective at different temperatures proportional to the differences in temperature of the circulating oil, a radiator means for each refrigerant, means for conducting the vapor of each refrigerant to its corresponding radiator to be relieved of its heat and condensed, and means intermediate each radiator and receptacle for returning the condensed refrigerants thereto.

8. In combination with an electric power transformer, an enveloping tank containing oil subject to convective circulation, means cooperative with said tank wall for extracting heat from said oil by conduction and radiation to the ambient air, and auxiliary cooling means for further reducing the oil temperature below ambient air temperature at the desired low temperature point of its circulation.
9. In combination with an electric transformer, an enveloping tank containing oil, said tank having an annular baffle member intermediate said transformer and tank wall to control convective circulation of said oil, means cooperative with said tank wall for extracting heat from said oil by conduction and radiation to ambient air, means for storing an additional reserve cooling medium so that it may yield its heat to the ambient air when the latter is at a minimum temperature, means retaining said reserve cooling medium at minimum temperature under rising ambient air temperature, and means for using the heat absorbing capacity of said reserve cooling medium more or less rapidly to reduce the temperature of said oil during relatively short peak overload conditions of said transformer.
10. In combination with an electric transformer having an enveloping oil jacket the oil content of which is subject to circulation, an exterior receptacle around said tank arranged to hold a refrigerant in contact with the tank wall to thereby extract heat from its oil content, a radiator means, means for conducting the vapor to the refrigerant to said radiator means to be relieved of its heat and condensed, means to return the condensed refrigerant to said receptacle, and means cooperative with said radiator to shower the latter with water to obtain additional cooling effects of evaporation.
11. In combination with an electric transformer having an enveloping oil jacket the oil content of which is subject to circulation, an exterior receptacle around said tank arranged to hold a refrigerant in contact with the tank wall to thereby extract heat from its oil content, a radiator means, means for conducting the vapor of the refrigerant to said radiator means to be relieved of its heat and condensed, means to return the condensed refrigerant to said receptacle, means for storing an additional reserve cooling medium so that it may yield its heat to the ambient air when the latter is at a minimum temperature, means retaining said reserve cooling medium at minimum temperature under rising ambient air temperature, and means for using the heat absorbing capacity of said reserve cooling medium more or less rapidly to reduce the temperature of said oil during relatively short peak overload conditions of said transformer.
12. In combination with an electric trans-
- former having an enveloping oil jacket the oil content of which is subject to circulation, a plurality of independent annular receptacles vertically spaced around said tank and respectively adapted to hold refrigerants effective at different temperatures proportional to the differences in temperature of the circulating oil, a radiator corresponding to each receptacle and in communication therewith, and auxiliary cooling means for further reducing the oil temperature at the desired low temperature point of its circulation.
13. In combination with an electric transformer having an enveloping oil jacket the oil content of which is subject to circulation, a plurality of independent annular receptacles vertically spaced around said tank and respectively adapted to hold refrigerants effective at different temperatures proportional to the differences in temperature of the circulating oil, a radiator corresponding to each receptacle and in communication therewith, means for storing an additional reserve cooling medium so that it may yield its heat to the ambient air when the latter is at a minimum temperature, means retaining said reserve cooling medium at minimum temperature under rising ambient air temperature, and means for using the heat absorbing capacity of said reserve cooling medium more or less rapidly to reduce the temperature of said oil during relatively short peak overload conditions of said transformer.
14. In combination with an electric transformer having an enveloping oil jacket the oil content of which is subject to circulation, a plurality of independent annular receptacles vertically spaced around said tank and respectively adapted to hold refrigerants effective at different temperatures proportional to the differences in temperature of the circulating oil, a radiator corresponding to each receptacle and in communication therewith, a water jacket surrounding the lower end of said oil jacket, and means for circulating cool water therethrough.
15. In combination with an electric transformer having an enveloping oil jacket the oil content of which is subject to circulation, a plurality of independent annular receptacles vertically spaced around said tank and respectively adapted to hold refrigerants effective at different temperatures proportional to the differences in temperature of the circulating oil, a radiator corresponding to each receptacle and in communication therewith, a water jacket surrounding the lower end of said oil jacket, means for circulating cool water therethrough, a cooling pipe coil within the lower end of said oil jacket in contact with the oil content thereof, means for storing a supply of reserve cooling medium for circulation through said cooling pipe coil, and means for controlling at will

the circulation of said reserve cooling medium through said cooling pipe coil.

16. In combination with an electric transformer having an enveloping oil jacket the oil content of which is subject to circulation, a plurality of independent annular receptacles vertically spaced around said tank and respectively adapted to hold refrigerants effective at different temperatures proportional to the differences in temperature of the circulating oil, a radiator corresponding to each receptacle and in communication therewith, a cooling pipe coil within the lower end of said oil jacket in contact with the oil content thereof, means for storing a supply of reserve cooling medium for circulation through said cooling pipe coil, means for dissipating heat from said stored supply when said cooling pipe coil is inactive, and means for controlling at will delivery of said reserve cooling medium through said cooling pipe coil.
17. In combination with an electric transformer having an enveloping oil jacket the oil content of which is subject to circulation, a plurality of independent annular receptacles vertically spaced around said tank and respectively adapted to hold refrigerants effective at different temperatures proportional to the differences in temperature of the circulating oil, a radiator corresponding to each

receptacle and in communication therewith, a cooling pipe coil within the lower end of said oil jacket in contact with the oil content thereof, means for storing a supply of reserve cooling medium for circulation through said cooling pipe coil, means for dissipating heat from said stored supply when said cooling pipe coil is inactive, and means for controlling at will delivery of said reserve cooling medium through said cooling pipe coil, a water jacket surrounding the lower end of said oil jacket, and means for circulating cool water therethrough.

18. In combination with an electric transformer, an enveloping tank containing oil for circulation therein relative to said transformer, means for applying a volatile liquid in juxtaposition with said oil whereby the former by its evaporation is adapted to extract heat from the latter, a radiator means for cooling and condensing the vapor of said volatile liquid, means to return the condensed volatile liquid to said means for applying the same in juxtaposition with said oil, and means to circulate cold water in juxtaposition with said oil at the desired low temperature point of the circulation of the latter.

In testimony, that I claim the invention set forth above I have hereunto set my hand this 12th day of June, 1926.

FRAZER W. GAY.
